United States Patent Office.

WILLIAM W. VIRDIN, OF BALTIMORE, MARYLAND.

Letters Patent No. 78,557, dated June 2, 1868.

IMPROVED TIDE-MOTOR.

The Schedule referred to in these Letters Patent and making part of the same.

TO ALL WHOM IT MAY CONCERN:

Be it known that I, WILLIAM W. VIRDIN, of Baltimore, in the county of Baltimore, and State of Maryland, have invented a new and improved Tide-Motor; and I do hereby declare that the following is a clear, full, and exact description thereof, reference being had to the accompanying drawings making part of this specification, in which—

Figure 1 is an elevation of one side of the improved motor.

Figure 2 is a plan view of the same.

Figure 3 is a vertical central section taken through the motor.

Figure 4 is an enlarged sectional view of several water-elevating buckets, arranged upon their internally-discharging pulley.

Figure 5 is a front elevation.

Similar letters of reference indicate corresponding parts in the several figures.

The object of this invention is to obtain motion and power sufficient, from the ebb and flow of tides through bayous or the mouths of inlets, to raise water to a proper height for furnishing a supply of water at distances remote from the point at which it is raised; also, to obtain power for driving machinery, and for other purposes.

The nature of my invention consists in arranging a water-wheel, of suitable description, upon a floating frame or buoy, and in so constructing such buoy, and arranging it in a passage formed between two walls, that all the water entering or passing out of an inlet shall be compelled to pass through the buoy and act upon the buckets of the wheel, thereby causing such wheel to rotate; and it also consists in so contriving the buoy, and the channel into which it is arranged, that this buoy shall rise and fall with the tide, and always maintain a proper position in the water, so that no water shall flow over or beneath it.

It also consists in the employment, in conjunction with a water-wheel and float or buoy, constructed as will be hereinafter described, as novel means for raising water, and delivering it into a trough or other conduit, whether said wheel rotates backward or forward, as will be hereinafter described.

To enable others skilled in the art to understand my invention, I will describe its construction and operation.

In the accompanying drawings, A represents two vertical walls, arranged parallel to each other, and constructed of masonry or other material, so as to form a water-way or passage of given dimensions at or near the mouth of a bayou or "inlet." These walls may terminate at their extremities in diverging walls, so as to form a proper inlet and outlet-passage for running water.

Between these two walls A A, and guided by means of the offsets *g g* and the vertical transverse cut-off B', is a float or buoy, B, which may be constructed of wood or metal, and which is made with bulk-head apartments *a a*, and inclined water-passages *b b*, as shown in figs. 2 and 3.

This buoy is made with the bulk-head apartments *a a* to increase its floating capacity, and with the bulk-head *a'*, covered by a removable or tightly-fitting cap, *a''*, to admit of the use of ballast, for causing the buoy to float at any required depth in water. A water-wheel, D, is arranged in the space formed in the top of the buoy, at the highest points of the two passages *b b*, and constructed with radial floats, *c*, in a manner similar to a common form of a propeller-wheel. This wheel is supported by a horizontal shaft, D', which has its bearings upon the standards H H, so that it will rotate freely in either direction. The wheel is fitted so nicely into the space formed for it in the upper side of the buoy that no material amount of water will escape over the upper side of this buoy, but all or nearly all the water will be caused to flow through the passages *b b*, and to act upon the floats of the wheel D, as indicated by the arrows in fig. 3.

As the tide rises, the buoy will rise with it, but maintain its proper depth in the water; and as the water cannot pass through the passage between the walls beneath the buoy, on account of the cut-off B', it will flow through the passages *b b*, and rotate the wheel D in one direction. When the tide ebbs, the water will return through the passages *b b*, and rotate the wheel D in an opposite direction.

By having the cut-off B' applied to the bottom of the buoy, so as to work up and down in a chamber, A', it will be seen that water cannot pass in a current beneath the buoy, but that the water will flow through passages *b b*, and will be caused to act upon the wheel D, to turn it.

For the purpose of steadyng the buoy against pressure of water, anti-friction wheels may be employed, as shown at C', &c, or in any other suitable manner.

I will now describe one practical mode of applying the power obtained from a wheel operated as above described, and employing it for a useful purpose. To one end of the shaft of the wheel D, a spur-wheel, E, is keyed, which engages with a similar wheel, E', upon a shaft, G', which also has its bearings in standards H, and which carries a flanged pulley or drum, G, shown in figs. 1, 2, and 4. This drum carries a number of water-elevating buckets, J, which are secured, at regular intervals apart, upon an endless open band or chain, k, which is of such length as to carry the buckets down into the side chambers J', in the buoy B. This chain or band is perforated, so that it will be caught and held by the studs j, upon the four angles of the rectangular drum G, and thus allow this drum to carry around the buckets as it is revolved. The four sides of the drum G are perforated, as shown at i i, which perforations or passages lead into an open circular space, h, and the buckets are so applied to their belt, k, that, as they ascend to their highest point, the water will flow from them, through the passages i, into said circular space, where it may be caught by a suitable trough, and conducted off to any desired point.

It will be seen, by reference to fig. 4, that the buckets J are constructed with chambers in both ends. This is for the purpose of causing them to elevate water from the chamber or well J, whether the wheel D be rotated forward or backward—whether the tide be ebbing or flowing. Instead of employing double-chambered buckets, single-chambered buckets will answer a similar purpose by having every alternate bucket inverted, this being the equivalent of the double-chambered bucket.

When it is desired to elevate water to a considerable height, a framework should be erected upon the buoy, and the shaft G', with its drum G, mounted upon said frame. In this case, the endless belt or chain k will pass around a large drum, fastened upon the shaft D' of the water-wheel D, and the toothed wheels will be removed. The drum last mentioned should be large enough to dip into the chamber or well J'.

The water may be supplied to the well or wells J', through valve-openings i' i', through their bottoms, on both sides of the cut-off B'. Thus the water flowing either into or out of the bayou will be forced upward, through said holes, into the wells, to be elevated by the endless chain or band of buckets.

In practice, the shaft G' may carry buckets upon both extremities, and elevate water from chambers or wells J' on both sides of the water-wheel.

Having described my invention, what I claim as new, and desire to secure by Letters Patent, is—

1. A floating vessel or buoy, B, constructed with water-passages through it, and provided with a cut-off, B', and a water-wheel, D, said buoy being arranged in a suitable passage-way for water, in such manner that the wheel D will be caused to turn both by the ebb and flow of the tide, substantially as described.

2. The buoy B B', constructed with bulk-head apartments, substantially in the manner and for the purposes described.

3. The chamber or chambers J', in combination with a buoy, B, having an aperture or apertures, i i, and constructed substantially as described, for the purpose of receiving water to be raised by the elevator J, substantially as described.

4. The endless chain of double-chambered buckets, in combination with a perforated drum, G, h, i, substantially in the manner and for the purposes described.

W. W. VIRDEN.
